UNITED STATES PATENT OFFICE.

WILLIAM H. LAWHORN, OF DALLAS, TEXAS.

DOUBLE-SERVICE ENVELOPE AND STATIONERY COMBINED.

Application filed July 7, 1926. Serial No. 120,912.

My invention relates to envelopes and more particularly to double service envelopes and double service stationery; and the object is to provide in a single piece of paper an original sheet for a letter, an order blank for return, a blank sheet for an answer or return letter, an original sealing strip, a return sealing flap, and as many sheets for manifolding as may be desirable or necessary. Another advantage is the means for closing the folds so that the contents of a letter or order cannot be read without unsealing the envelope. Another object is to provide stationery for keeping duplicate records of all correspondence more economically. Other objects and advantages will be fully explained in the following description and the invention will be more particularly pointed out in the claims.

Reference is had to the accompanying drawings which form a part of this application.

Fig. 1 is an illustration of the combined envelope and letter and order blank and return letter, showing the device just as struck from a sheet of paper.

Fig. 2 is the same sheet reversed.

Fig. 3 shows the original forwarding envelope for first-class mail.

Fig. 4 is a similar view of an envelope provided with a seal to prevent unauthorized persons looking in the end of the envelope and reading the contents of the letter.

Fig. 5 illustrates the same envelope for returning first-class mail.

Fig. 6 is a cross section, taken on the line 6-6 of Fig. 4.

Fig. 7 is a cross section, taken on the line 7-7 of Fig. 5.

Fig. 8 is a longitudinal section, taken on the line 8-8 of Fig. 3.

Fig. 9 illustrates the envelope folded and the ends of the folds sealed.

Fig. 10 illustrates the letter ready to go forward as second-class matter.

Fig. 11 is an enlarged view showing the entire envelope and letter just as cut from a sheet of paper.

Fig. 12 is the reverse side of Fig. 11.

Similar characters of reference are used to indicate the same parts throughout the several views.

In the drawings the body 1 is for a letter or an order or any other suitable matter on the inside and the address on the outside 2.

The envelope is provided with a seal flap 3

for forwarding first-class matter, and it has a flap 4 which serves as a seal for the return of first-class matter and the same flap can be used for the return address. The envelope has a window 5 which serves when second-class matter is being forwarded to render visible instructions to withdraw the flap 4 for unfolding or opening of the envelope. To forward second-class matter, run the flap 4 down inside of the body 1 as shown in Fig. 10, this flap bearing instructions such as "Pull flap here" as shown in Fig. 12.

When there is advertising to be done, the lateral flaps 6 and 7 may be used on one face for this purpose and the other faces may be used for first-class matter or for a return letter or similar letter.

Extensions 8, as many as may be desired, can be used and these extensions are foldable inwardly and may be used for letters on one side either going or coming in and the address on the other side or advertising matter. Carbon sheets with second sheets 80 may be used when copies are wanted. The flap 4 will lock the carbon and second sheets in position to prevent slipping when being manipulated by the operator.

Seal flaps 9 may be used at the ends of the envelope to seal the envelope to prevent unauthorized persons from reading any of the contents of the letter, and these flaps 9 need not be gummed because they lock automatically by reason of the fold. The paper may be slotted along the dotted outline.

In operation, the letter or order is written on the face of plate 1 and the address on the outside 2. The flaps 6, 7 and 8 can then be folded on the body 1. The messages may be written on either side of the sheet and folded inwardly. The letter or order or both can be folded inwardly, and then sealed with the side sealing flap 3 which may be gummed. If only second-class matter is to be sent, the flap 4 may be used to lock the device closed as in Fig. 10. When the device has first-class matter the seal 3 must be broken before the envelope can be opened. When the device is to be returned with first-class matter it is sealed with the flap 4 by gum or otherwise as shown in Fig. 5 for the return. The flaps 9 are used to seal the end to prevent unauthorized persons from reading the contents of the letter. Either end may be sealed with the flap 9.

The stationery sheets can be prepared, as

shown in Figs. 11 and 12 with printed matter or other indices for return address and any other suitable or useful instructions may be printed on the stationery. The device may 5 be provided with a thread or cord 11 attached thereto for unsealing the letter by cutting the seal 3 with the cord or thread.

What I claim is:

10 A commercial article of stationery combining an envelope, a letter sheet, a return letter sheet, an order blank and a return envelope; said letter sheets being arranged to be folded upon said order blank and then collectively folded to letter size for mailing; a protective flap formed upon a remote edge of one of said letter sheets and 15 adapted, when said sheets are folded to over-

lap and bind the folds together to prevent unauthorized reading of said letter sheets when so folded; a sealing flap integral with 20 one side of said order blank for sealing said article in mailing form for primary use; a sealing flap integral with the other side of said order blank for sealing said article for secondary use; a means for a directing address on the reverse side of said order blank and on said latter sealing flap; means for postal instructions on said secondary sealing flap and visible through an opening in said 25 primary sealing flap when said article is used 30 for second class matter.

In testimony whereof, I set my hand, this 22nd day of June, 1926.

WILLIAM H. LAWHORN.
